LIQUID DISPENSING SYSTEM AND A CAP
THEREFOR

Stephen Mezzapesa, New York, N. Y.

Application June 27, 1939, Serial No. 281,322

10 Claims.

(Cl. 225—22)

This invention relates to a liquid dispensing system for liquid held in bottles or containers under gas pressure. An example of a container other than a bottle is a can. The liquid is charged or impregnated with gas, usually carbon dioxide gas. Beer and ginger ale are examples of such contents. In my preferred form, a special type of cap is used, usually a crimped cap commonly known as a "crown" cap. This cap has its outer shell, usually of metal, provided with an opening which is closed off by the gasket inside the cap. The cap when crimped on a bottle will hermetically seal the contents of the bottle. The opening is provided in the shell of the cap to permit the tube of the dispensing mechanism to be inserted through it to pierce the gasket inside and enter the bottle. An adjustable detachable ring is clamped to the neck of the bottle which acts with the other parts of the dispensing mechanism to fasten the latter firmly to the top of the bottle. The dispensing mechanism is set in operative position on the bottle including the piercing of the cap without the loss of gas from the bottle.

Other objects and advantages will become apparent upon further study of the description and drawing in which:

Fig. 1 is a partial elevation and section of my dispensing mechanism shown mounted on a bottle with a "crown" cap.

Fig. 2 is a partial elevation looking along the line 2—2 of Fig. 1.

Fig. 3 is a section through a cap with one form of gasket.

Fig. 4 is a section through a cap with another form of gasket.

Fig. 5 is a section through a crimped cap with a gasket of the type of Fig. 4, shown mounted on a neck of a bottle with a tube shown extending through the cap and its gasket, the other parts of the dispensing mechanism being omitted, and

Fig. 6 is a partial section of the dispensing mechanism shown mounted on the neck of a bottle without a cap.

Bottle 7 is provided with a cap having a metallic shell 8 with an opening 9. Two types of gasket may be provided to come inside of shell 8. Gasket 10, shown in Fig. 4, is waterproof and gas-tight and sufficiently soft so that when shell 8 is crimped over the neck of the bottle it will hermetically seal the contents of the bottle. A suitable material would be rubber, either the natural product or synthetic. While sufficiently soft for sealing, yet the rubber should be stiff enough not to bulge out appreciably through

opening 9 due to the gas pressure in the bottle. The gasket shown in Fig. 3 comprises two parts, the usual cork layer 11 and a washer 12 above it of a stiff waterproof paper which can however be readily pierced by the point 13 of tube 14. A paraffin impregnated paper would be suitable for washer 12.

The dispensing mechanism comprises a tube 14, having a tip 15 with a point 13 and slots one 10 of which is shown at 16. Tube 14 is inserted into the bottle through the opening 9 in shell 8, point 13 piercing the gasket. In Fig. 5 is shown tube 14 after it has been inserted into bottle 7 and pierced gasket 10.

15 Fitting over the usual bulge 17 formed on the neck of a bottle with a crimped cap, is clamping ring 18 which consists of two parts attached to each other by a hinge 19. The other end of said parts are fastened to each other by a bolt with a winged nut 20. A flange 21 is provided on one 20 end of clamping ring 18. Within limits said ring can be mounted on bottles having necks and bulges of different diameters, hinge 19 and the bolt with wing nut 20 providing adjustability.

25 When ring 18 is clamped on the bottle, flange 21 comes under the lower edge of bulge 17 preventing said ring from being pulled up off the bottle. On each part of ring 18 is provided a lug 22. Engaging the lower edge of each lug 22 is a

30 hooked arm 23. The upper ends of said arms are riveted to an externally threaded sleeve 24 which fits slidably over a flange 25 formed on a tubular member 26. A rubber block 27 fits over the lower end of member 26 under flange 25.

35 Above flange 25, member 26 is provided with an external annular groove 28. A flange formed on the upper edge of internally threaded sleeve 29 rides in said groove. Sleeve 29 is provided with capstan arms 30. The threading inside of sleeve 29 40 engages with the threading on the outside of sleeve 24. The rotation of sleeve 29 manually by means of arms 30 may be used to raise or lower sleeve 24 with respect to member 26 and its flange 25. When sleeve 29 is rotated so as to

45 raise sleeve 24 relatively to member 26, the hooked lower ends of arms 23 pull up on lugs 22, causing flange 25 to press down rubber block 27 hard against the top of shell 8. Lugs 22 are T-shaped with a bulb 50 at the bottom of the stem. This permits the hooks of arms 23 to be slid horizontally into position on the lugs past the bulbs, the heads of the T preventing the arms from going too far.

50 Tube 14 passes up through member 26, a clearance 32 being provided between the outside of

said tube and the inside of said member. Above groove 28 is a tube 31 whose bore is in communication with clearance 32. Connected to tube 31 is a hand air pump 33 for forcing air into clearance 32. Above tube 31, clearance 32 is enlarged and has a block 34 of rubber or the like set therein. The enlarged upper end of member 26 has external threading 35. A sleeve 36 is internally threaded engaging threading 35. Sleeve 36 has an inturned flange 38 coming inside of member 26 for engaging the top of rubber block 34. Capstan arms 37 are provided on sleeve 36 for manually rotating the latter. When sleeve 36 is rotated, flange 38 is caused to bear down on the top of rubber block 35, causing the latter to expand and tightly grip tube 14 and press against the inside of member 26, effectively sealing off the upper end of clearance 32.

A branch pipe 45 leads off sideways from the upper end of tube 14 and is provided at its outer end with a faucet 39, the discharge from which is controlled by a valve 40.

In using my system, tube 14 is set in member 26 so that its tip 15 is raised up to come inside member 26. Sleeve 36 is set so that its flange 38 compresses block 34 sufficiently that there can be no appreciable leakage of air or gas from clearance 32 yet the block will permit tube 14 to be pushed through it as desired. Clamping ring 18 is fastened on the neck of the bottle by tightening wing nut 20. The hooks on the bottom of arms 23 are slid over lugs 22. Sleeve 29 is rotated to pull up on sleeve 24 and arms 23 compressing rubber block 27 on the top of shell 8 making an airtight chamber above and around the edges of opening 9 in said shell. Said chamber is in communication with clearance 32. Tube 14 is then pressed downward so that its point 15 passes through opening 9 and pierces gasket 10. In this operation no appreciable amount of gas is lost from the bottle, whatever leakage there is past tube 14 where it pierces gasket 10 is stopped by block 34. The liquid in bottle 7 will enter tube 14 through openings 16 (only one being shown) in tip 15. If there is sufficient gas pressure in the bottle the liquid will rise to valve 40. Operating valve 40 will allow liquid to be discharged from faucet 39. If the gas pressure is not sufficient pump 33 is used to get up sufficient pressure. When a quantity of liquid has been discharged from the bottle and no more liquid will come out when valve 40 is opened, pump 33 is operated again. Pump 33 forces air into the bottle through clearance 32, opening 9 and between the pierced gasket and tube 14 where it passes through. With the air pressure thus obtained, the liquid is discharged from faucet 39 when valve 40 is opened.

The type of apparatus shown in Fig. 6 is especially adapted for bottles having thin necks closed by corks instead of crimped caps. The particular bottle 41 shown has no bulge on its neck only a lip 42 at its top. To suit this condition clamping ring 18 is set on the neck with its flange 21 on top coming under lip 42. The rest of the apparatus, including the part not shown, is the same as that of Figs. 1 and 2, except that tip 15 is left off the bottom of tube 14, leaving said bottom blunt.

In using the apparatus as in Fig. 6, tube 14 is pulled up within member 26 and sleeve 29 is turned so that hooked arms 23 cause block 27 to be pressed down directly on lip 42. The blunt lower end of tube 14 is then pushed down on the cork (not shown) in the neck of the bottle forc-

ing the cork into the bottle and out of the way. From here on the operation of the apparatus is the same as described above for Figs. 1 and 2.

While the crimped cap, often called a "crown" cap, is my preferred form, other types of cap, with a gasket inside their outer shell, may be used such as a screw cap with the neck of the bottle correspondingly threaded. A screw cap lends itself readily to having its tough outer shell of other material than metal such as a phenol condensation product.

The term bottle as used in the claims is intended to be broad enough, except where it is clear by the context that a bottle is meant, to cover in addition to the usual glass bottle, a gas-tight container with some form of bead, enlargement or irregularity with which the adjustable detachable clamping ring can engage.

I claim:

1. In a liquid dispensing system for liquid held under gaseous pressure in a container, a cap fastened to the container for hermetically sealing the same, said cap having a tough outer shell and a gasket inside, said gasket comprising a gas-tight but readily pierceable material, the shell having an opening in its top and the gasket initially being intact across said opening, a tube inserted into the container through the opening in the shell and by piercing the gasket, the bottom of the tube reaching substantially to the bottom of the container, means for sealing the outside of the tube to the container, said means providing an air passage between itself and the tube, means for pumping air into said passage the air being forced past the gasket into the container from said passage, and valve means on the tube for manually controlling the discharge of the liquid from the container.

2. In a liquid dispensing system for liquid held under gaseous pressure in a bottle, a cap crimped on the bottle, said bottle having an enlargement on its neck below where the cap is attached, a detachable clamping ring set on the bottle over said enlargement, the lower portion of the ring coming below the enlargement and being of less inside diameter than the outside diameter of said enlargement, said cap having a tough shell and a gas-tight readily pierceable gasket inside, the shell having an opening in it and the gasket initially being intact across said opening, a tube inserted into the bottle through the opening in the shell and by piercing the gasket, and means on the tube adjustably engaging said clamping ring and providing an air passage outside the tube, the lower end of said passage being at the cap, means for pumping air into said passage, the air being forced past the gasket into the bottle, and valve means on the tube for manually controlling the discharge of the liquid from the bottle.

3. In a liquid dispensing system for liquid held under gaseous pressure in a container, having a neck, closure means for closing the neck of the container, a tube extending into the container through said closure means, said tube reaching substantially to the bottom of the container, detachable clamping means set on the neck of the container, encasement means encircling said tube, said means being near one end, in sealed engagement with the outside of the tube, the other end of said means adjustably engaging the clamping means and in sealed engagement with the closure means, said encasement means providing an air passage outside of the tube, means for pumping air into the air passage, the air

forcing its way from said passage by the outside of the tube where the latter passes through the closure means into the container, and valve means on the tube for manually controlling the discharge of liquid from the container.

4. In a liquid dispensing system for liquid held under gaseous pressure in a container, closure means for closing the container, a tube inserted into the container by piercing the closure means, the bottom of the tube reaching substantially to the bottom of the container, said tube being provided at its bottom with a point for facilitating the piercing of the closure means, means for sealing the outside of the tube to the container, said latter means providing an air passage outside of the tube, the bottom of said passage being at the closure means, means for pumping air into the air passage, the air forcing its way from said passage by the outside of the tube where the latter passes through the closure means into the container, and valve means on the tube for manually controlling the discharge of liquid from the container.

5. In a liquid dispensing system for liquid held under gaseous pressure in a container having a neck, closure means for closing the neck of the container, a tube inserted into the container by piercing the closure means, a detachable clamping ring set on the neck of the container, encasement means encircling said tube, said encasement means being provided with a circumferential groove, a sleeve having at its upper portion a radially extending flange rotatably mounted in said groove said sleeve having a threaded portion, a second sleeve, below said first sleeve in threaded engagement therewith, a second flange below said groove extending radially from the encasement means, a rubber block coming inside said second sleeve and located between said second flange and the top of the closure means and means depending from said second sleeve detachably engaging the clamping ring, whereby the rotation of said first sleeve compresses the rubber block between the second flange and the top of the closure.

6. In a device for attaching air pumping and liquid dispensing apparatus to a container having a neck, clamping means in the form of a ring detachably fastened to the neck of the container, lugs on said ring extending radially therefrom, members on the apparatus extending downwardly therefrom, each member having a hooked lower end coming under a lug.

7. In a liquid dispensing system for liquid held in a container, having a neck, closure means for closing the neck of the container, a tube extending into the container through said closure means, said tube reaching substantially to the bottom of the container, encasement means encircling said tube and in slidable engagement therewith, means for fastening the encasement means to the neck of the container, said encasement means being in sealed engagement near one end with the outside of the tube, the other end of said means being in sealed engagement with the closure means, an air passage being

provided out of communication with the air in the tube leading from the inside of the encasement means to the inside of the container, means for pumping air into the air passage, and valve means on the tube for manually controlling the discharge of liquid from the container.

5 8. In a liquid dispensing system for liquid held in a container, closure means for closing a discharge opening in the container, a tube extending into the container through said closure means, said tube reaching substantially to the bottom of the container, a member on said tube outside of the closure means, leaving a space between the inside of said member and the outside of the tube for an air passage, means for fastening said member to the container, a gasket located between the upper portion of said member and the tube sealing off the top of said passage, a second gasket between said member and the outside of the closure means for sealing off the lower portion of the passage, said tube being slidably mounted in said gaskets, means mounted on said member for pumping air into the passage between said gaskets, forcing air into the passage and past the closure means into the container, and valve means on the tube for manually controlling the discharge of liquid from the container.

10 9. In a liquid dispensing system for liquid held in a container, closure means for closing a discharge opening in the container, a tube extending into the container through the closure means, said tube reaching substantially to the bottom of the container, a member on the tube outside the closure means in sealed engagement with the tube and closure means, providing an air passage out of communication with the air in the tube, means for fastening said member to the container, said tube being slidable with respect to said member, means attached to said member for pumping air into the passage and past the closure means into the container, and valve means on the tube for manually controlling the discharge of liquid from the container.

15 45 10. In a liquid dispensing system for liquid held in a container having a neck, a cap for closing the neck of the container, said cap having a tough outer shell and a gasket inside, said gasket comprising a gas-tight but readily pierceable material, the shell having an opening in its top and the gasket initially being intact across said opening, a tube inserted into the container through the opening in the shell and by piercing the gasket, the bottom of the tube reaching substantially to the bottom of the container, means for sealing the outside of the tube to the container, means for attaching the sealing means to the neck of the container independently of the cap, an air passage being provided through the sealing means past the gasket into the container and out of communication with the air in the tube, means for pumping air through said passage into the container, and valve means on the tube for manually controlling the discharge of liquid from the container.

STEPHEN MEZZAPESA.
